UNITED STATES PATENT OFFICE.

DICK M. VESEY, OF FORT WAYNE, INDIANA.

MOLD-INSERT-FEEDING MECHANISM.

Application filed March 1, 1923. Serial No. 622,055.

To all whom it may concern:

Be it known that I, DICK M. VESEY, a citizen of the United States, residing at Fort Wayne, in the county of Allen and 5 State of Indiana, have invented new and useful Improvements in Mold-Insert-Feeding Mechanisms, of which the following is a specification.

The invention relates to mechanisms for 10 feeding inserts into molds, and it is particularly directed to means for feeding upon the pins of a rubber-heel mold the washer inserts that are embedded in the heel to act as abutments for the heads of nails or other 15 means to attach the heel to the shoe or boot.

The object of the invention is to provide 20 a simple mechanism by which the washer inserts are effectively and automatically fed upon the pins of a rubber heel mold, thus accomplishing a large saving over the hand feed method commonly in use.

The invention consists in vertically arranged guiding members upon which the washer inserts are stacked and which are 25 adapted to register with the washer supporting pins of a heel mold and a movable member in cooperative relation to the guiding members and having washer supporting means thereon.

30 The invention is illustrated in simple form in the accompanying drawings in which Figure 1 is a perspective view of a mechanism embodying the invention; Fig. 2 an elevational view of the guide members and supporting frame; Fig. 3 a bottom plan view of the same; Fig. 4 a plan view of the valve supporting member; Fig. 5 a cross-section of the same on line 5-5 of Fig. 4; Fig. 6 a cross-section on line 6-6 of Fig. 4; Fig. 7

40 a plan view of the valve member supported on its supporting member; Fig. 8 a fractional view, partly in section, of the mechanism illustrating the method of supporting the stacks of washers on the guide members;

45 Fig. 9 a similar view illustrating the relative position of the parts after a washer has been released; Fig. 10 a plan view of one of the stack supporting members; Fig. 11 an enlarged plan view of a washer; Fig. 12 50 a central cross-sectional view of the same and Fig. 13 another form of washer having the invention applied thereto.

In the drawings I have illustrated the invention as applied to a single unit for the 55 deposition of a set of washers simultaneously upon the pins of a single heel cavity in a

mold; but it is my purpose to apply the invention, in readily understood manner, so that by a single operation of the movable member a set of washers for each heel cavity 60 in a gang mold will be released simultaneously.

Referring to the present embodiment of the invention the device consists of a washer supporting and guiding frame formed by 65 the top member or plate 1 having the depending corner posts 2, upon the lower reduced ends of which a support 3 is detachably secured by the feet 4 that are threaded on the said reduced ends. The feet are 70 adapted to support the frame at the proper height relatively to the heel mold 5. Guide rods 6 depend from the top member 1 and they are arranged in exact accordance with the arrangement of the pins 7 that project 75 upwardly from the heel mold. The latter pins are reduced at their upper ends to form shoulders 7^a thereon upon which the washers 8 will lodge when released from the frame. The washers are placed on the guide 80 rods 6 in any convenient manner. Each washer is formed with a central boss 8^a or 8^b (Fig. 13) for abutting the washer above it in a stack and thereby space the washers 85 in the stack for the purpose described later.

Where the support 3 is solid, as in the present embodiment, apertures 9 are formed therein through which the lower ends of the guide rods 6 extend axially, the apertures being of sufficient diameter to permit the 90 washers to pass through them readily. The only function of the member 3 is to support the controlling valve or slide 10, hence it may be in any desired form.

In the present illustration the controlling 95 slide or valve 10 is pivoted at 11 to the support 3, a revoluble movement of the slide in a single unit being convenient but not essential, it being apparent that the slide may have any relative movement desired. 100 Apertures 12 are formed in the slide and are arranged in exact accordance with the arrangement of the guide rods so that when the slide is moved in proper direction the apertures will be brought into register with the guide rods axially, and to permit this axial registration to occur each aperture 12 is formed with a slotted extension 13 in which the associated guide rod 6 is operative. In the inactive position of the slide shown 110 in Fig. 8 the guide rods are in the slots 13. When the slide is moved in proper direction

the said movement causes the axial alignment or registration of the apertures and the guide rods. A stop 15 on the support 3, operative in a slot 16, limits the latter movement of the slide.

Adjacent to each aperture 12 a forked member 14 is secured to the slide, the forked portion of each member 14 being elevated sufficiently to allow the same to pass over 10 a washer, the forks passing onto opposite sides of the guide rod and engaging the bottom of the washer next above and thereby supporting the stack of washers on the rod. In the inactive or normal position of the 15 slide the lowermost washer of each stack contacts with the upper face of the slide—over the slots 13. The instant the apertures 12 in the slide axially register with the guide rods and hence axially register with the 20 washers on the rods, the lowermost washer of each stack drops through the aperture onto the pin below it; the forked members have already engaged under the washers next above the lowermost washers and hence 25 support the stacks of washers on the several guide rods. The reverse movement of the slide withdraws the stack supporting members and causes the slots 13 to move under the same. When the supporting members 30 have disengaged from the stacks, the stacks drop down into contact with the slide, and the device is ready for another releasing operation.

It is apparent that any number of sets of 35 the guiding members may be supported on a frame and the slide extended so that the lowermost washers of the several stacks shall be released simultaneously, thus feeding the washers to a plurality of heel forms in a 40 mold, the general practice being to construct the mold with a large number of heel-forming cavities so that a large number of heels shall be produced at each use of the mold.

45 Various modifications in the structure and in the arrangement of parts will be suggested to one skilled in the art hence I do not wish to be limited to the precise structure and combination of parts herein described.

50 What I claim is:

1. In a mechanism of the class described, a vertically disposed guide for a column of 55 insert washers, a movable member normally supporting the column of insert washers and having means therein adapted to register with the lower end of said column to release the lowermost washer-insert when the said member is moved toward said column, and a member secured to the movable member and adapted to be moved thereby toward, and into, said column immediately above the 60 lowermost washer-insert prior to the release of the latter washer-insert.

65 2. In mechanism of the class described, a vertically disposed guide for a column of

insert washers, a slide normally supporting the said column and having an aperture therein adapted to be brought, when the slide is moved, into register with the lower end of the column for releasing the lowermost washer-insert and a member secured to the slide and adapted to be projected thereby into the said column immediately above the lowermost washer-insert prior to the release of the latter washer-insert.

75

3. In a mechanism of the class described, a base having an aperture therein, a guide for a column of washer-inserts suspended in said aperture, a slide movably mounted on the base and normally supporting the said column of washer-inserts, the slide having an aperture therein adapted to be brought into register with the aperture in the base and with the lower end of said column for releasing the lowermost washer-insert, the guide extending through the aperture in the movable slide, and means carried by the slide and adapted to be moved into the said column immediately above the lowermost washer-insert for temporarily supporting the portion of said column above the same.

80

4. In mechanism for feeding washer-inserts to heel-molds, the combination of a vertically disposed guide adapted to receive a column of stacked washer-inserts, a fixed member having an aperture therein concentric with the guide, a movable member on the fixed member normally supporting the washer-inserts and having an aperture therein adapted to be moved into register with the aperture in the fixed member for releasing the lowermost washer-insert, and a member secured to the movable member and overhanging the aperture therein and adapted to enter the column of washer-inserts between the lowermost washer and the washer next above prior to the release of the said lowermost washer.

95

5. A washer-insert feeding mechanism for heel-molds comprising an apertured base, a vertical guide extending into the aperture and adapted to receive a column of washer-inserts, a movable member on the base normally supporting the washer-inserts and having an aperture therein through which the guide extends, said last named aperture being adapted to register with the aperture in the base when the movable member is operated for releasing the lowermost washer-insert, and a member on the movable member overhanging the aperture in said movable member and spaced from said member and adapted to enter the column of washer-inserts immediately above the lowermost washer prior to the release of the latter washer for supporting said column.

110

6. A washer-insert feeding mechanism for heel-molds comprising a base having a plurality of apertures therein, a plurality of guides suspended in the said apertures re-

115

120

125

130

- spectively, a slide movably mounted on the base and adapted to support a plurality of washer-inserts on each guide and having a plurality of apertures therein through which the guides extend respectively, said latter apertures being adapted by the movement of the slide to be caused to register with the apertures in the base for releasing the lowermost washer-insert from each guide and a plurality of members secured to the slide and overlying the apertures therein respectively and adapted by the movement of the slide to be projected laterally above the said lowermost washer-inserts prior to the release of the said inserts.
7. In a mechanism for feeding washer-inserts to a heel-mold having upwardly projecting pins, a fixed apertured member, the apertures in which are adapted to register with the pins, a plurality of fixed vertical guides projecting through the said apertures respectively and adapted to receive the inserts in stacked relation, an apertured movable member above the fixed apertured member normally supporting the stacked inserts and adapted to be moved to cause its apertures to register with the apertures in the fixed member for releasing the lowermost inserts and means carried by the movable member and adapted to engage the stacked inserts above the lowermost inserts thereof prior to the release of the latter inserts, for temporarily supporting the stacks.

In witness whereof I have hereunto subscribed my name this 27th day of February, 1923.

DICK M. VESEY.
